ATTORNEYS.

UNITED STATES PATENT OFFICE.

THEODOR O. L. SCHRADER, OF NEW YORK, N. Y.

PENCIL.

SPECIFICATION forming part of Letters Patent No. 350,948, dated October 19, 1886.

Application filed June 15, 1886. Serial No. 205,196. (No model.)

To all whom it may concern:

Be it known that I, THEODOR O. L. SCHRADER, a resident of New York city, in the county and State of New York, have invented an Improvement in Pencils, of which the following is a full, clear, and exact description, reference being made to the accompanying drawings, in which—

Figure 1 is a central longitudinal section of my improved pencil. Fig. 2 is a central longitudinal section of a modification of the same. Fig. 3 is a central longitudinal section of another modification of the same. Fig. 4 is a central longitudinal section of what is shown in Fig. 3 in a different position.

This invention relates to a new construction of pencil for holding a loose lead; and it consists in the new combination of parts herein-after stated.

In the drawings, the letter A represents the case or outer sheath of the pencil-holder, the same being bored longitudinally to receive within its bore the lead B. At the end the sheath A carries rigidly attached thereto a slotted projecting tube, a, of small diameter, but large enough to embrace the lead B, said tube a terminating in biting-jaws b, which, when compressed, are adapted to hold the lead B, as in Fig. 1, but which, when loosened or opened, as in Fig. 2, will allow the lead to slide freely.

C is a sliding "contracting" tube—that is, a tube which is constructed to press the jaws b against the lead whenever said tube is in one position, (see Figs. 1 and 3,) and to allow the said jaws to open when it (said tube C) is in the other position. (See Figs. 2 and 4.) The tube C is held in one position—the normal or contracting position—by a spring, d, which is confined in place within a tubular extension, e, of the case or sheath A. The said extension is of the same external diameter as the sheath A, and adapted to receive within it the smaller tube, C, and the spring d. The spring d is between the outer circumference of the tube C and the inner circumference of the extension e.

When the tube C is of the construction shown in Fig. 1—that is, adapted to press the jaws against the lead in its converging or tapering mouth—the spring d, bearing against a flange, f, at the upper end of the tube C, will normally hold said tube in the elevated position against the end of the sheath A; but when the tube C is of the construction shown in Figs. 3 and 4—to wit, adapted to hold the jaws against the lead by contact with its diverging or flaring mouth—the spring d, pressing against a shoulder, f*, of the tube C, beneath it and against the end of the sheath A, will normally hold said tube in the lowered position, as shown in Fig. 3.

In the position shown in Figs. 1 and 3 the lead is firmly held by the jaws b. In order to move the lead, the tube C must be pulled forward, as in Fig. 2, or pushed upward, as in Fig. 4, so as to open the jaws and release the lead.

Fig. 2 shows two leads held in the same sheath, the same sheath being provided with the means specified for holding and releasing each of said leads.

By arranging the tube C to slide within the extension e of the sheath A the lower end of the sheath proper is utilized as an abutment, (see Figs. 1 and 4,) and the parts are confined within a periphery substantially equal to that of the sheath A.

I claim—

The combination, in a pencil, of the sheath A, having projecting jaws b, with the sliding tube C, of less diameter than sheath A, fixed tube e, of substantially the same diameter as the sheath A, and spring d, the said spring being confined by the tube e and surrounding the tube C, the end of the sheath A serving as an abutment, as specified.

THEO. O. L. SCHRADER.
